CLAIM

The ornamental design for a packaging and display box for a TV game controller, as shown and described.

DESCRIPTION

FIG. 1 is a perspective view of a packaging and display box for a TV game controller having a specific cut out pattern showing my new design;

FIG. 2 is a left side view thereof;

FIG. 3 is a bottom view thereof; and,

FIG. 4 is a rear elevational view thereof.

The broken lines are for illustrative purpose only and form no part of the claimed design.
